US0D1075677S

(12) **United States Design Patent** (10) **Patent No.:** **US D1,075,677 S**
(45) **Date of Patent:** **** May 20, 2025**

(54) **CAP FOR BATTERY**

(71) Applicant: **LG Energy Solution, Ltd.**, Seoul (KR)

(72) Inventors: **Kwang-Su Hwangbo**, Daejeon (KR);
Kwang-Hun Ko, Daejeon (KR);
Do-Gyun Kim, Daejeon (KR); **Da-Som**
Lee, Daejeon (KR); **Min-Ki Jo**,
Daejeon (KR); **Su-Ji Choi**, Daejeon
(KR)

(73) Assignee: **LG Energy Solution, Ltd.**, Seoul (KR)

(**) Term: **15 Years**

(21) Appl. No.: **29/905,936**

(22) Filed: **Oct. 27, 2023**

(30) **Foreign Application Priority Data**

Aug. 1, 2023 (KR) 30-2023-0030070

(57) **CLAIM**

The ornamental design for a cap for battery, as shown and described.

DESCRIPTION

FIG. 1 is a top front perspective view of a cap for battery, showing our new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom rear perspective view thereof; and,

FIG. 9 is a top front perspective view thereof, shown in an environment of use.

The broken lines of even length in FIG. 9 represent environmental structure that forms no part of the claimed design.
